US00D730404S

(12) **United States Design Patent**
Yu et al.

(10) **Patent No.:** **US D730,404 S**
(45) **Date of Patent:** **** May 26, 2015**

(54) **DISPLAY SCREEN OR PORTION THEREOF
WITH ICON**

(71) Applicant: **Samsung Electronics Co., Ltd.,**
Suwon-si (KR)

(72) Inventors: **Seock-Hyun Yu**, Seoul (KR); **Ji-Hye
Myung**, Yongin-si (KR)

(73) Assignee: **Samsung Electronics Co., Ltd.,**
Suwon-si (KR)

(**) Term: **14 Years**

(21) Appl. No.: **29/457,131**

(22) Filed: **Jun. 7, 2013**

(30) **Foreign Application Priority Data**

Feb. 23, 2013 (KR) 30-2013-0009502

(57) **CLAIM**

The ornamental design for a display screen or portion thereof with icon, as shown and described.

DESCRIPTION

FIG. 1 is a front view of a display screen or portion thereof with icon, showing our new design; and,

FIG. 2 is a front view of a second embodiment thereof. The broken line showing of the display screen is included for the purpose of illustrating environmental structure and forms no part of the claimed design.

1 Claim, 2 Drawing Sheets
